MACHINE FOR INTERPRETING AND PRINTING PERFORATED RECORDS

Jonas E. Dayger, Binghamton, N. Y., and Asa N. Miller, Hallstead, Pa., assignors to International Business Machines Corporation, New York, N. Y., a corporation of New York

Application December 4, 1950, Serial No. 199,132

4 Claims. (Cl. 101—93)

1

This invention relates to tabulating machines and more particularly to machines of the type capable of sensing perforated records, interpreting the meaning of the perforations and controlling the operation of the printing mechanism to print the amounts represented by the perforations on the records.

Machines of the above type have been utilized for printing on perforated records to form checks issued for payment of some monetary transaction and machines of the above type have been found to be highly accurate in their operations when used commercially. Nevertheless, any single instance of improper printing should be guarded against however rare its occurrence. Such improper operations may result from wear of parts, dust, change in adjustment of parts, the probability of an unpunched or off-punched hole in the card, omission of a hole in a column, a broken plug wire, etc., and the signaling to the user of such a change or condition is an indication of requirement of service for such machines to prevent repetition of improper printing. It is, therefore, the main object of the present invention to provide a machine for printing under control of a perforated record an amount represented by the perforations of the record and to provide comparing or checking means which controls means for preventing improper printing. For purposes of this invention the comparing means is shown as comprising two electrical circuits.

In machines of the above class it is desirable that provision be made for detecting improper machine operations of a nature that would cause the completing of one comparing circuit before its appointed time. Accordingly, it is an object of the present invention to condition the comparing circuits for the detection of an irregularity in the functioning of the comparing means as a result of improper machine operations which would lead to errors.

It is another object of the present invention to analyze a record to cause under control of the analyzing means the setting of a single set of type bars to print an amount, preferably on the perforated record; to provide means controlled by contacts of the single set of type bars and a second sensing means to determine whether the type bars have been accurately set to print the amount represented by the perforated record; and to prevent the printing operation when a type bar has not been accurately positioned.

Another object of the invention is to provide a novel means for detecting a crooked position

2

of a card which might be sufficient to cause an error. This checking means acts within a margin of error to detect cards which would have a smaller degree of misalignment than would be detected by the comparing mechanism.

The machine is also provided with means for detecting a blank card, a complete zero field and a failure of the hammers to fire.

As is well known, machines of the above class are controlled by records which are perforated in columns and the perforation placed in the column is indicative of the particular digit represented in that column and may be either the digits 0 to 9 inclusive and two special perforations representing the numerals 11 and 12. The present machine is provided with a mechanism, preferably electrically controlled, which determines whether the type bar has been properly positioned to represent any of the digits 0 to 9 in each of the columns from which printing is effected.

It is a further object of the present invention to cause the aforesaid checking and comparing mechanisms to control the operation of the machine and more specifically it is an object of the present invention to cause the machine to be stopped whenever it is determined that improper printing will result from any of the aforementioned causes. The machine is preferably so constructed that the machine will stop before the type hammers will be released to cause the improper printing of the result.

By constructing the machine in the above described manner it will not be possible to improperly print amounts, and the operator will be signaled whenever such improper printing is liable to occur. Hence the machine will operate in a more efficient manner than heretofore, and more perfect operations thereof will ensue.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a central longitudinal sectional view of the machine.

Fig. 2 is a sectional view taken at one side of the machine.

Fig. 3 is a view in side elevation disclosing in normal position the means controlled by the type bars for causing the closure of checking contacts at the time the type bars are stopped.

Fig. 4 is a perspective view of the contact clos-

ing devices to more clearly show their arrangement and construction.

Fig. 5 is a timing diagram showing the timing desirable to close certain electrical contacts and circuits.

Figs. 6 and 6a placed one beneath the other comprise an electrical wiring diagram of the preferred form of the invention.

Card feeding mechanism

In more detail, 10 (Fig. 2) represents the main driveshaft of the machine. This may be driven in any suitable manner as by an electric motor through belt 11 rotating a pulley attached to a shaft 157. A uni-directional coupling 12 is interconnected between shaft 10 and 157.

From shaft 10 a worm 13 (Fig. 2) drives worm wheel 14 secured to a shaft 15 to which is also secured a box cam 16. A pivoted cam follower arm 17 has a roller 18 at one end riding in the cam groove and at the other has connection to an arm 19 through adjustable rod 20.

Arm 19 is secured to a shaft 21 having arms 22 (see Fig. 1) in pin and slot engagement with pickers 23 mounted for reciprocation in the frame of the machine. This reciprocating picker mechanism is adapted to advance one record card at a time from the supply stack or magazine 24.

Shaft 157 through gears 25 shown in Fig. 2 drives a parallel shaft 26 which has threaded sections 27 meshing with worm gears 28 on feed roller shafts 29 to drive feed rollers 30 (Fig. 1) constantly. The card which is advanced by the picker passes into the bite of the first pair of feed rollers 30 to the left in Fig. 1 and is subsequently guided to the analyzing or perforation reading devices which comprise brushes 31 and a contact roller 32. These brushes and contact roller are of conventional structure such as is commonly used in electrically controlled tabulating machines.

After passing the analyzing brushes 31 the cards pass to the second pair of feed rollers 30 which advance each card to a pair of intermittently driven rollers comprising upper spring 45 pressed rollers 33 and lower rollers 34 which engage the edge of the card. These rollers 33 and 34 advance the card to printing position at which time they momentarily pause in their rotation to stop the feeding of the card to permit printing on the card in accordance with the preceding analysis.

This interruption in the advance of the card is accomplished as follows: Rollers 34 are secured to a shaft 35 (Fig. 1) journaled in the frame of the machine and having attached at one end a gear 36 (Fig. 2) meshing with a gear 37 on shaft 38 on which shaft is also a gear 39 adapted to be driven by a mutilated gear 40 free on the continually running shaft 15.

During the rotation of shaft 15 the gear 40 will pick up gear 39 by means of the teeth thereof to advance the card to printing position, upon reaching which, the toothless portion of gear 40 moves into locking engagement with gear 39 as shown in Fig. 2. After printing has been effected gear 39 is again engaged for rotation and the card is fed forward to a conveying means (Fig. 1) comprising rollers 41 and tracks 42 which convey the card to a suitable stacker 43 where they are collected. The shafts upon which rollers 41 are secured are adapted to be continually driven by reason of the gear connections 44 to the shaft 26 as shown in Fig. 2. It is the frictional engagement of rollers 41 with 75

the upper surface of the card which causes the card to be advanced along the tracks 42.

It will be apparent that by altering the relationship between gear 40 and wheel 14, the position on the card in which printing is effected will be altered. That is, if the gear 40 is so adjusted that the cam portion is earlier effective in its time of operation, the card will be sooner interrupted in its advance and a lower line will receive the printing impression.

Printing mechanism

For effecting the printing on the record cards as they successively pass through the machine a plurality of type bars 45 (Fig. 1) is provided. These bars are all mounted for reciprocation in the frame of the machine and each has a connection through a spring-pressed pawl 46 to a crosshead 47 (Fig. 4). Thus, in Fig. 1, upon movement of crosshead 47 to the left, the pawls 46 through frictional engagement with bars 45, will move the bars concurrently in the same direction.

The bars may be arrested at any point in their travel and subsequently the pawls 46 will disengage and permit the further movement of the crosshead 47. Upon the reverse movement of crosshead 47 the shoulders 185 (Fig. 3) of the bars 45 will be engaged thereby to positively move the bars to restored position. For reciprocating crosshead 47 the following mechanism is provided.

As shown in Fig. 2 the crosshead 47 is connected at its ends to blocks 48 slidable upon rods 49 and having pivoted link connections 50 to a follower arm 51 pivoted at 52. Arm 51 has a roller 53 cooperating with the cam groove of a box cam 54 mounted on a shaft 55 connected through worm gear 56 and worm 57 to the constantly running shaft 10. The arrangement and timing of the parts is such that the type bars 45 are advanced under the influence of pawls 46 synchronously with the movement of a card past the analyzing or sensing brushes 31.

If a perforation at, say, the 5 position on the card is under the sensing brushes, the corresponding type representing 5 will be at the printing line. The establishment of an electric circuit through the index point perforations by the brushes is adapted to energize a magnet 58.

There are a number of these magnets 58, each magnet being related to a corresponding type bar 45. The energization of any magnet is adapted to release a pawl device 59 through a wire 61 and latch 62 and allow it to engage one of the ratchet teeth 60 on the bar 45. After pawl 59 has engaged the teeth 60 further movement of the type bar 45 to the left in Fig. 1 is prevented. The type bars 45 are positioned during a passage of a card past the brushes. Subsequently these type bars are held during the period that a card passes from the analyzing station to printing position and during the printing operation. After the printing operation, pawls 59 and latches 62 are positively restored in the following manner.

Secured to shaft 55 is a cam 63 (Fig. 1) against which presses the roller of an arm 64 and which latter is pressed upwardly by a spring 65 acting through an arm 66 on shaft 67. The shaft 67 has secured thereto arms 68 which carry a restoring plate 69. Arms 70 pivoted on a rod 70a and having a pin and slot connection to arms 68 carry a restoring plate 71. By this construction cam 63 is adapted to move plate 69 to the left to restore pawls 59 and plate 71 is moved upwardly to

restore latches 62 and their connected wires 61.

For each type bar 45 there is an individual hammer 72 which is adapted to strike the particular type 73 on the type bar which is at the printing line. The hammers are pivotally mounted on a rod 74 carried by a hammer bail or bar 75 and depend for their actuation upon movement of said bar. The bar 75 is pivoted on the frame of the machine by means of pintles coaxial with rod 74 and has springs 76 biasing the bar in a clockwise direction in Fig. 1.

To the middle of bar 75 there is pivoted a cam follower arm 77 bifurcated to straddle shaft 55 and having a roller 77a in cooperation with a cam 78. Fixed to one face of the cam 78 is a cam member 79 which cooperates with a projection 80 of the cam follower arm 77.

As the cam 78 revolves, by virtue of the shaft 55 being driven in the manner previously described, it cooperates with the arm 77 through its follower roller 77a, gradually retracting the hammers 72 in a counterclockwise direction against the tension of springs 76.

As the roller 77a leaves the high point of the cam 78, member 79 engages the projection 80 and upon continued rotation of the cam the projection 80 drops from the member 79 and the springs 76, thus released, turn the common bar 75 in a clockwise direction to swing the hammers 72 against type 73 thus effecting printing.

It was mentioned hereinabove, that means are provided in the present machine for preventing the printing operations to be effected, whenever the checking means provided herein detect that the differentially positioned type bars are not in conformity with the sensed designations. To this end, provision is made to prevent the hammers from being tripped in order to prevent printing of the data, which mechanism will now be described.

By circuits to be described later, a timed impulse energizes a control magnet 89 (Fig. 1) which causes armature 88 to be attracted. The attraction of the armature allows an arm latch 87, secured to common bar 75, to disengage from armature latch surface 100. It is this operation that permits the common bar 75 to rotate clockwise, in the manner previously explained, to swing the hammers 72 against the type 73. Spring 107, confined on one end by stop 85, returns armature 88 to its original position when the magnet 89 becomes deenergized.

In Fig. 1, the reference character 81 designates a printing platen journaled in the frame of the machine and adapted to be turned by frictional engagement with the passing card to prevent excessive wear at any one place. The inking ribbon devices are of conventional form and require no detailed description, the ribbon 82 being guided along the platen 81 and beneath the record card.

In the event that the values sensed by the sensing brushes and those set up in the type bars do not conform, the timed impulse previously mentioned is suppressed, thus printing for the particular cycle will be suppressed and is explained in the following manner. The suppression of the timed impulse prevents energization of magnet 89. Thus, armature 88 remains in engagement at surface 100 with latch arm 87 which prevents further cooperation between roller 77a and cam 78 as the high point of the cam passes by the follower roller. For the same reason cooperation is suppressed between cam member 80

and block 79; thus common bar 75 will not displace hammers 72 for the particular cycle.

It should also be mentioned that a plurality of cam elements 55a (Fig. 2) are provided and secured to shaft 55 for controlling the operations of the related contacts, such as CC1 to CC13 and CB1 to CB4. The timing arrangement of the operations of these contacts is shown in Fig. 5.

10 Mechanism for operating the type bar contacts

The mechanism for closing the type bar contacts is shown particularly in Figs. 1, 3 and 4. For each type bar there is provided a spring urged pawl 46 pivotally secured to the crosshead 47 at shaft 159. When pawl 59 is unlatched, due to the energization of magnet 58, it will engage a tooth 60 on type bar 45 as the crosshead 47 moves to the left. Concurrently, spring urged pawl 46 is moved clockwise by cam surface 163 to cooperate with plunger 160, which, in turn, actuates a T-shaped lever 164 at surface 162, the T lever being carried by two levers 165 and 167 loosely mounted on rods 166.

The lever 165 is shaped with an arm to actuate a contact 168a. In the first denominational order shown in Fig. 4 the armed lever 165 is at the upper end of the T lever 164 while in the next denominational order the lever 165 is at the lower end of the T lever and operates a contact 168a in a lower level (see also Fig. 5 of Patent No. 2,247,914).

This construction is desirable in order to provide for the proper side spacing of the contacts 168a and the operating mechanism since each is substantially wider than a type bar 45. The above arrangement is repeated for the next adjacent orders of the set of type bars. Each of the type bars will cause the closure of a related pair of contacts 168a.

40 Circuit diagram

Referring to the wiring diagram (Figs. 6, 6a) certain of the mechanical parts are shown in diagrammatic form in these figures. In Figure 6a, M designates the electrical motor which by the belt and pulley connection previously referred to, drives the main drive shaft 10 of the machine. This shaft through the gearing described drives the picker devices which rotate the feed rollers to advance and feed the card past the analyzing brushes 31 which are not shown on Figs. 6, 6a (see Fig. 1) and in passing the brushes the usual card lever CL is pressed by the cards thus closing the card lever contacts CLa.

To start the machine in operation, the operator first closes the main line switch 121 and thereafter the start key 122 is depressed which upon closure of its contacts establishes a circuit from line side 92 through these contacts to a start key relay R55 and to line side 93. The energization of relay R55 closes relay contacts R55a and R55b which complete a circuit from line side 92 through relay contacts R55a, stop key contacts 123, relay contacts R55b, motor relay R124 and relay R58 in parallel with the motor relay, to line side 93. The energization of relay R124 closes motor relay contacts 124a to establish a circuit from line side 92 through these contacts to motor M and to line side 93. The energization of motor M causes the feeding of the cards so that card lever CL closes its contacts CLa to cause the energization of card lever relays R53 and R54 which are in parallel, through a circuit described as follows: from line

side 92, relay contacts R58a now closed, card lever contacts CLa, relays R53 and R54 to line side 93.

Referring now to Fig. 5, it will be noted that the card lever contacts CLa close near the end of a cycle and remain closed through 150° of the next cycle, thereby maintaining relays R53 and R54 energized throughout this period. Cam contacts CC1 and other CC contacts to be herein-after referred to are controlled by cams on the shaft 55 and from the timing diagram in Fig. 5, it will be seen that the cam contacts CC10 close toward the end of a cycle before card lever contacts CLa and remain closed during the beginning of the next cycle to pick up relay R45 through a circuit from line side 92, through cam contacts CC10, relay contacts R56b now closed, relay contacts R54a, stop relay R45 to line side 93. Cam contacts CC10 open at 20° in the machine cycle but relay R45 is held energized to 178° by cam contacts CC5, CC9 and CC8. The energization of relay R45 closes relay contacts R45c to establish a holding circuit for the motor relay R124, as follows: from line side 92 through relay contacts R58a and R53a, stop key contacts 123, relay contacts R45c, motor relay R124 and relay R58 to line side 93.

Cam contacts CC5, CC8 and CC9 are timed to close before cam contacts CC10 and remain closed for a considerable time after cam contacts CC10 open which establishes a holding circuit for stop relay R45 from line side 92 through cam contacts CC8, CC9 and CC5, relay contacts R45a, relay R45 to line side 93. It will be seen from Fig. 5 that after the card lever contacts CLa open, relay R58 and motor relay R124 are held energized by the motor cam 100 until the end of the cycle when the card lever contacts again close, through a circuit from line side 92, relay contacts R58a, motor cam 100, motor relay R124 and relay R58 to line side 93.

Once relays R53 and R54 are energized, start key 122 may be relinquished for now the machine will continue to run until the cards in the hopper are exhausted providing all the machine tests are satisfactory and relay contacts R45c remain closed.

Checking circuits

The present invention concerns itself primarily with the means for determining whether a type bar is positioned to print a digit in accordance with the perforation of the record card and is described in connection with the wiring diagram of Figs. 6, 6a and the timing diagram of Fig. 5.

A typical checking circuit operation consists in energizing a pair of relays, one relay being energized by an associated thyratron ignited by a checking brush circuit timed two cycles points after its corresponding sensing brush timing. The other relay is energized by the type bar contacts which provide a circuit also effective two cycle points after the corresponding sensing brush timing.

Now, as the cards are advanced to the sensing station, the brushes 31 which are not shown on Figs. 6, 6a (see Fig. 1) and conducting roller 32 are effective to complete circuits to the connected printing control magnets 58 at the differential times the perforations in the record cards are presented to the said brushes and roller. In the present invention a set of checking brushes 90 is positioned at a point in the path of card travel to sense the perforations two cycle points after the brushes 31.

For purposes of description of this invention only four checking brushes 90 are shown in Fig. 6 but it should be understood that a checking brush and comparing circuit may be supplied for each card column sensed by the sensing brushes 31. Referring now to Fig. 6, a relay R9 is in series with a thyratron 95 in the checking brush circuit. In order to energize relay R9, it is first necessary to ignite the thyratron in series therewith. Upon the presence of a perforation, contact is made between checking brush 90 and a contact strip 91, and a circuit is closed through cam contacts CC3 which from Fig. 5, it will be seen, are closed during the time the perforation is analyzed by the brushes. Circuit breaker contacts CB1 and CB2 are provided in the checking brush circuit and are adapted to be closed by dentated cams 98 and 99 respectively which are driven by the shaft 55 (Fig. 2) so as to rotate once for each operation of the machine. The contacts are operated by the teeth of dentated cams 98 and 99 so as to make contact on the line of index and break ½ index point after the line of index. This checking brush circuit causes the thyratron 95 to be ignited and can be traced as follows: From line conductor 92, circuit breaker contacts CB1 and CB2, cam contacts CC3, relay contacts R44c, contact strip 91, hole in card, brush 90, plug connection 116, normally closed relay contacts R11d, resistance 94, to line side 93. It should be noted that an additional potential is placed on thyratron grid 95b through resistance 108 by the closing of the checking brush circuit. Resistances 108 and 94 act as a voltage divider and the value of each resistance is so determined to enable the thyratron to fire. Condenser 109 is connected between the cathode 95a and the grid 95b of the thyratron 95 and provides a predetermined time delay for the firing of the thyratron 95 in response to the application of the additional voltages transferred to the thyratron 95 upon closure of the checking brush circuit. The extent of the delay is determined by the values of resistance 108 and condenser 109. Cam contacts CC1 close 1° after the front edge of the card insulates brush 31 from contact roll 32 and remains closed until 261° of the cycle. Relay R9 is picked up through thyratron 95 and held energized under the influence of cam contacts CC1 through a circuit as follows: line side 92, cam contacts CC1, relay R8, thyratron 95, to line side 93. The energization of relay R9 closes relay contacts R9a in the circuit controlled by the type bar contacts (Fig. 6) and transfers relay contacts R9b (Fig. 6a) in the checking test circuit which is more fully described hereinafter.

From Fig. 6 it will be seen that a relay R11 is in circuit connection with relay contacts R10b, type bar contacts 168a and circuit breaker contacts CB1 and CB2 through relay contacts R44d and cam contacts CC4. While the magnet 58 stops the type bar, an appreciable time is required to cross the checking contacts 168a and from Fig. 5 it will be seen that this occurs about two cycle points after the perforation is analyzed by the brush 31, hence relay R11 is picked up at substantially the same time that relay R9 is energized, by means of the following circuit: line side 92, circuit breaker contacts CB1 and CB2, cam contacts CC4, card lever relay contacts R44d, type bar contacts 168a, normally closed relay contacts R10b, thence through the pick-up coil P of duo wound relay R11 to line side 93. A holding circuit for relay R11 will be maintained under the control of cam contacts CC1 from line side 92, cam contacts

CC1, relay contacts R11c, holding coil H of relay R11 to line side 93. The energization of relay R11 opens relay contacts R11d in the thyatron circuit and transfers relay contacts R11b (Fig. 6a) in the checking test circuit. Relay R9 is held energized through its holding circuit under the control of cam contacts CC1.

The relay R8 when energized closes relay contacts R9b in the checking test circuit while energization of relay R11 closes relay contacts R11b also in the checking test circuit. If both relays R9 and R11 are energized simultaneously thereby closing their respective checking test circuit contacts, the circuit through the checking contacts shown at the top of Fig. 6a will remain closed. However, if either relay R9 or R11 is energized at a time dissimultaneous with the energization of the other relay, the corresponding relay contacts in the checking test circuit will not remain closed, thereby opening the circuit and causing deenergization of relay R45.

After the checking contacts R9b and R11b and all others in series therewith are set up, a test is made upon the opening of check test cam contacts CC5. It will be seen from Fig. 5 that cam contacts CC5 open at 178° after all card index positions from 1 to 9 have been analyzed, thereby establishing a circuit through the checking contacts as follows: relay R45, relay contacts R45a, checking contacts (shown at top of Fig. 6a), cam contacts CC9 and CC8 to line side 92. If there has been a dissimultaneous energization of relays R9 and R11 or any other pair of checking relays, the open circuit will cause deenergization of relay R45.

Relay R45 controls contacts R45c located in series with motor relay R124 in the holding circuit for the motor relay. When a test impulse is not available for keeping relay R45 energized, contacts R45c open and the motor stops running thereby preventing machine operation.

To summarize, the checking relays R9 and R11 are picked up at substantially the same point in the machine cycle to condition the checking test circuit which is tested later in the cycle to determine the presence or absence of an error in the printing and sensing of data on the card.

The checking brush circuit and the circuit controlled by the type bar contacts are further conditioned for detection of improper operations which would lead to errors. These improper operations include, for example, a shorted condenser 109 which is in series with the grid 95b and cathode 95a of thyatron 95. This condition would permit a transient pulse to energize the grid and fire the thyatron 95 before its appointed time. Another improper operation can result from a short circuit occurring between adjacent checking brushes 90 in which the short causes the relay in one of the thyatron circuits to be energized when its associated card columnar position is blank. From Fig. 6 it will be seen that a relay R10 is in series with relay contacts R9a and circuit breakers CB4 and CB3 which make at 5° before the line of index and break on the line of index. In the event that relay R9 be energized before its appointed time and close relay contacts R9a, relay R10 will be energized through a circuit from line side 92, through circuit breakers CB3 and CB4, relay contacts R9a, relay R10 to the line side 93. The energization of relay R10 opens relay contacts R10b in the circuit controlled by the type bar contacts, thereby preventing relay R11 from picking up. Relay contacts R9b transfer in the checking test

circuit while relay contacts R11b remain stationary to preclude a test impulse from coming through to the stop relay R45.

Provision is also made for the converse of this situation. A number of improper operations can effect the positioning of the type bars 45 (Fig. 3), as, for example, when pawl 59 is unlatched, there is a possibility that it will not follow into the correct tooth 60 to correctly position the type bar. There is also the possibility that the spring biased pawl 46 may not fully restore to the position shown in Fig. 3 because of a binding action in its pawl pivot shaft due to an accumulation of dust or dirt. In this instance the position of the bar 45 would be lagging and present an early tooth to an unlatched pawl 59. In any event these conditions might result in the positioning of a type bar ahead of its true position. If relay R11 is energized prematurely, the normally closed relay contacts R11d open in the checking brush circuit to prevent energization of relay R9 at its appointed time. Relay contacts R11b transfer in the checking test circuit while relay contacts R9b remain stationary to preclude a test impulse from coming through to the stop relay R45.

Checking for correct card alignment

It is desirable to check the position of the card as it passes through the interpreter to determine whether it is properly aligned. This is performed by two brushes 102 and 103 positioned at opposite ends of the card in the checking brush group and explained in connection with the wiring diagram. If a card passes through in proper alignment, these brushes ride on the card and are insulated from the contact roll 91.

Brushes 102 and 103 are arranged in parallel in the aligning check circuit and are in series connection with a pair of cam contacts CC11 and CC12 which lead to the cathode 97a of thyatron 97. Referring to Fig. 5, it will be seen that cam contacts CC2, CC11 and CC12 close at the beginning of a cycle to test the alignment of the card. Cam contacts CC2 and CC11 close at the 11th index point position and open slightly before the 10th index point position. CC12 closes before the 11th index point position, remaining closed until slightly after the 11 index point. This overlapping in the closure of the three cam contacts permits the alignment test to be made.

If a card is somewhat askew when passing the group of checking brushes 90, contact with roll 91 will be made by either brush 102 or 103 to establish a circuit at the test time from line side 92, through cam contacts CC2, relay contacts R54b, contact roll 91, brush 102 or 103, cam contacts CC11 and CC12, resistance 96, to line side 93. Thyatron 97 functions in the same manner as thyatron 95 which has been described in connection with the checking brush circuit. A condenser 110 is connected between the cathode 97a and grid 97b of thyatron 97 and provides a predetermined time delay for the firing of thyatron 97. The extent of the delay is determined by the values of condenser 110 and resistance 112.

Cam contacts CC13 close near the end of a cycle, remaining closed until 261° of the next cycle (Fig. 5) and are therefore closed when the alignment test is made. If the card is wrongly positioned and thyatron 97 fires, relay R46 is picked up through a circuit as follows: line side 92, cam contacts CC13, relay R46, thyatron 97, to line side 93. Energization of relay R46 opens normally closed relay contacts R46a in the check-

ing test circuit. When cam contacts CC8 open at 178° to test for the checking of the type bar position for a complete zero or blank position as explained hereinafter, the checking test circuit will be found to be open, causing relay R45 to deenergize and the machine to stop running.

Means for enabling printing operation when type bars are properly set and preventing a printing operation when type bars are improperly set

From Figs. 5 and 6a it is seen that cam contacts CC7 normally send an impulse to the hammer suppression magnet 89 through relay contacts R45b which transfer upon energization of relay R45. If between 178° to 198° of a cycle no agreement is found between any checking brush circuit relay and its corresponding relay in the circuit controlled by the type bar contacts, relay R45 deenergizes and at 212° cam contacts CC7 send an impulse to relay R56 which holds through relay contacts R56a and cam contacts CC8. The machine will not stop immediately upon the deenergizing of relay R45 but will coast until coming to rest by force of friction. Now at 325° cam contacts CC10 will attempt to pick up relay R45, but relay contacts R56b now being open prevent relay R45 from becoming energized and the machine will coast to a subsequent stop.

For example, if a brush 31 does not transmit a sufficiently large impulse to energize a print magnet 58, the checking brush 90 will nevertheless energize the more sensitive thyratron circuit and relay contacts R9b will transfer in the checking test circuit without transfer of relay contacts R11b. At the test time immediately following, the holding circuit for relay R45 is found open causing relay R45 to be deenergized. Relay contacts R45c are opened and the stick circuit to motor relay R124 will be opened and the machine will coast to a stop. It will be noted that the printing hammers 72 are released for operation earlier in the cycle by energization of hammer suppression magnet 89 which occurs when relay R45 is picked up. Relay contacts R45b will then transfer to energize relay R56 through cam contacts CC7 and the hammer suppression magnet will become deenergized leaving the hammer bail 75 in a latched position.

Checking for successful determination of printing operation

It should be noted (Fig. 6a) that the holding circuit for relay R45 extends through cam contacts CC9 and hammer bail contacts 101 in parallel therewith. If agreement is found, then print hammers 72 will operate and the hammer bail 75 closes its contacts 101 at 269° to test whether the hammers actually have been released. Cam contacts CC9 open between 275° and 285°, but if hammer bail contacts 101 close at 269°, the hold circuit for relay R45 continues and the machine keeps running. However, if hammer bail contacts 101 are opened when cam contacts CC9 open, relay R45 deenergizes and the machine stops even if an agreement is ascertained.

Checking of type bar position for a complete zero or blank position

From Fig. 6a it will be seen that relay R45 is in series with the "d" contacts of the relays R9, R14, R18 and R22 of the checking brush circuit. The "d" contacts are arranged in parallel with cam contacts CC8 which are timed to open at 178° after all the card index positions have been

read. In the event that there is no perforation analyzed at the 1-9 index point positions, none of the "d" contacts will be closed when cam contacts CC8 open thereby causing the holding circuit for relay R45 to be opened and resulting in the deenergization of relay R45. Relay contacts R45c then open in the holding circuit for the motor relay R124 and the machine coasts to a stop.

A similar stopping of the machine occurs when the card is punched all zeros. If the card has a complete zero field punched thereon, the relays R9, R14, R18 and R22 of the checking brush circuit will remain deenergized since cam contacts CC4 are not timed to close to set up the checking brush circuit until after the zero time of checking sensing time (Fig. 5). Failure of each of the checking relays R9, R14, R18 and R22 to energize results in the "d" contacts of each relay remaining open. When cam contacts CC8 open between 178° and 198° to test the status of the "d" contacts, the holding circuit for relay R45 will open if none of the "d" contacts have closed, resulting in the deenergization of relay R45.

In the event that the machine operator desires to eliminate the checking operations performed by the "d" contacts of the checking brush circuit relays, plugs 104 and 105 and plugwire 106 are provided. When plugwire 106 is in place in plugs 104 and 105, the "d" contacts are shunted and become ineffective.

While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. In a cyclically operating machine in which records are fed in succession past first and second sensing stations and having means at the first station to sense a column of one record, for value representations, the combination of a set of type bars, one for each order, each type bar having an individual hammer mounted on a common bail, resilient means for directing the hammers against the type bars to effect printing, type bar positioning means, means under control of said sensing means to control said type bar positioning means to effect a differential positioning of the type bar to select type for printing the value, supplemental sensing means at the second station to sense a corresponding column of the record for value representations after such representations have been sensed by the first sensing means, comparing means jointly controlled by the supplemental sensing means and said type bar for comparing the item designations and the setting of the type bar for detecting agreement or non-agreement, means controlled by the comparing means for restraining the hammers from being actuated by said resilient means when the comparing means detects a non-agreement, a machine control device controlled by the comparing means for stopping machine operation when the comparison is dissimilar, and means responsive to actuation of the hammer bail by said resilient means for controlling the machine control device when the comparing means detects an agreement.
2. In a record controlled machine in which a type bar is differentially positioned under con-

13

trof of sensing means sensing perforations in a record to select a type for printing, and supplemental sensing means are provided to sense the same perforations in the record after such perforations have been sensed by the first named sensing means, the combination of a first circuit, means under control of said type bar for completing said first circuit when positioned under control of said first named sensing means to select a type, a second circuit, means under control of said supplemental sensing means for completing said second circuit upon sensing a perforation, both of which circuits are concurrently completed when the type bar has been positioned to select a type which corresponds with the perforation sensed by the supplemental sensing means, means for prematurely completing either the first or second circuit in response to an improper completion of the related circuit, a plurality of control relays, means for energizing each of said relays responsive to premature completion of the related circuit, and means controlled by each relay when energized upon a premature completion of the related circuit to disable the other circuit.

3. In a record controlled machine in which a type bar is differentially positioned under control of sensing means sensing perforations in a record to select a type for printing, and supplemental sensing means are provided to sense the same perforations in the record for value representations after such perforations have been sensed by the first named sensing means, the combination of a first circuit, means under control of said type bar for completing said first circuit when positioned under control of said first named sensing means to select a type, a second circuit, means under control of said supplemental sensing means for completing said second circuit upon sensing a perforation, both of which circuits are concurrently completed when the type bar has been positioned to select a type which corresponds with the perforation sensed by the supplemental sensing means, means for prematurely completing either the first or second circuit in response to an improper completion of the related circuit, a plurality of control relays, means for energizing each of said relays responsive to premature completion of the related circuit, means controlled by each relay when energized upon a premature 50 completion of the related circuit to disable the other circuit, an additional control relay energized upon completion of said second circuit, and

14

a checking circuit for determining the further operation of the machine controlled by the control relay energized in response to completion of said first circuit and said additional control relay energized in response to completion of said second circuit.

4. In a record controlled machine in which a type bar is differentially positioned under control of sensing means sensing perforations in a record to select a type for printing, and supplemental sensing means are provided to sense the same perforations in the perforated record after such perforations have been sensed by the first named sensing means, the combination of a first circuit, means under control of said type bar for completing said first circuit when positioned under control of said first named sensing means to select a type, a second circuit, means under control of said supplemental sensing means for completing said second circuit upon sensing a perforation, both of which circuits are concurrently completed when the type bar has been positioned to select a type which corresponds with the perforation sensed by the supplemental sensing means, means for prematurely completing either the first or second circuit in response to an improper completion of the related circuit, a first control relay in said first circuit and energized in response to the completion of the first circuit, 15 means controlled by said first relay when energized to disable the second circuit upon premature completion of said first circuit, a second control relay in said second circuit and energized in response to the completion of the second circuit, a third circuit, a third control relay in said third circuit, means controlled by said second relay when energized to complete said third circuit to energize said third control relay, and means controlled by said third relay to disable the first circuit upon premature completion of said second circuit.
